UNITED STATES PATENT OFFICE.

WILBUR STUART SHEPPARD, OF COLORADO SPRINGS, COLORADO.

ASSORTING-TRAY.

1,372,098.

Specification of Letters Patent. Patented Mar. 22, 1921.

Application filed November 20, 1919. Serial No. 339,394.

To all whom it may concern:

Be it known that I, WILBUR STUART SHEPPARD, a citizen of the United States, and a resident of Colorado Springs, in the county 5 of El Paso and State of Colorado, have invented certain new and useful Improvements in Assorting-Trays, of which the following is a specification.

My invention relates generally to trays 10 for papers of various kinds and particularly to the maintenance of checks, deposit slips and the like in orderly piles during posting, thereby increasing the efficiency while lowering the possibility of error in 15 posting to the wrong account.

It is a purpose of my invention to provide a tray of the above described character which is of extremely simple and inexpensive construction, and which is provided 20 with means for securing the tray in fixed position upon a table.

It is also a purpose of my invention to provide a support adapted to be used in conjunction with the tray for supporting 25 the papers so as to increase the speed and accuracy of posting.

I will describe one form of tray embodying 30 my invention and one form of support and will then point out the novel features thereof in a claim.

In the accompanying drawings:—

Figure 1 is a view, showing in perspective, 35 one form of tray and support embodying my invention;

Fig. 2 is a longitudinal sectional view of Fig. 1;

Fig. 3 is a plan view of the tray shown 40 in the preceding views, in applied position upon a table and in working position with respect to an adding machine.

Similar reference characters refer to similar parts in each of the views.

Referring specifically to the drawings, T designates generally the tray which is 45 formed in the present instance from a single piece of metal or any other suitable material, the same comprising a base portion or plate 15 including a relatively wide portion 15^a and a narrow portion 15^b. One 50 longitudinal edge and the forward transverse edge are provided with upstanding flanges 16 and 17, respectively, which are shaped in the form shown to properly confine the checks and deposit slips upon the 55 base plate 15 and to facilitate their removal and application. As illustrated to advan-

tage in Fig. 1, the base plate 15 is upstruck transversely and longitudinally at various points to provide posts 18^a, 18^b and 18^c which are arranged to coact with each other 60 and with the flanges 16 and 17 to form a plurality of compartments for the reception of the checks and deposit slips. In the present instance, the wide portion 15^a of the base plate 15 is provided with posts 18^a that 65 coact with each other and with the flanges 16 and 17 to provide a check receiving compartment indicated at C. The portion 15^a is also provided at a point rearwardly of the post 18^a with other posts 18^b which coact 70 with certain of the posts 18^a and the flange 16 to provide another check receiving compartment C'. The narrow portion 15^b is provided with posts 18^c that are arranged to form two compartments C² and C³ that 75 are arranged parallel to each other at right angles to the compartments C and C'. It will be noted that the posts 18^c nearest to the rear end of the tray are relatively short so that they will not interfere with the depositing and changing of the deposit slips from compartment C² to compartment C³. As 80 illustrated to advantage in Fig. 1, one edge of the tray is cut at an angle and provided with an arcuate slot 19 which is adapted 85 to receive a screw head for confining the tray as a unit upon a table, as will be more fully described hereinafter.

Figs. 1 and 2, show the compartments C' provided with a support S that is of angular formation so that in its applied position 90 it is inclined with relation to the base plate 15 whereby papers deposited thereupon will assume an inclined position and thus facilitate the reading of the indicia on the papers. 95

Referring now to Fig. 3, T designates a table provided at its marginal edge with a molding 20, and adjacent one end of the table is adapted to be placed an adding machine designated at A. Upon the table adjacent the adding machine is arranged the tray T in such manner that the forward edges of the base plate 15 abut the molding 20 of the table. After the tray has been moved to this position, it is rigidly secured 105 upon the table by the placing of a screw in the table at such a point that the recess 19 of the tray will engage the shank of the screw and thus serve as a locking means for the tray.

In practice, a stack of checks to be posted with their faces turned upwardly are placed

within the compartments C' and on the support S, the bookkeeper standing at the narrow end of the tray so that the checks are clearly visible from this position. A stack of deposit slips is placed in the compartment C² in such manner that the signatures on the slips are disposed adjacent the signatures on the checks, thus facilitating the comparison of the signatures of the corresponding slips and checks. Now as the signatures, amounts, etc., are red, checked and posted, the deposit slips are turned over one by one face down into compartment C³, whereupon corresponding checks are likewise turned over one by one and placed down into compartment C². It will thus be seen that by virtue of the tray, the checks and deposit slips are kept in orderly piles while posting, and because of the relative disposition of the papers, it will be obvious that speed and accuracy with which the items may be posted is greatly increased.

Although I have herein shown and described only one form of tray embodying my invention, it is to be understood that various changes and modifications may be resorted to without departing from the spirit of the invention or the spirit and scope of the appended claim.

Having thus described my invention, I claim:

A tray of the character described comprising a base plate, flanges formed on the edges of said base plate, posts formed on said base plate and coacting with each other and with said flanges to provide two pairs of compartments, and a recess formed in one edge of the base plate for receiving a screw for the purpose described.

WILBUR STUART SHEPPARD.
